UNITED STATES PATENT OFFICE.

WEBSTER C. ESTES, OF NEW YORK, N. Y.

DESIGN FOR A TURNED WOODEN BOX.

SPECIFICATION forming part of Design No. 32,119, dated January 23, 1900.

Application filed November 13, 1899. Serial No. 736,882. Term of patent 14 years.

To all whom it may concern:

Be it known that I, WEBSTER C. ESTES, a citizen of the United States, residing at New York, (Brooklyn,) in the county of Kings and State of New York, have invented and produced a new and original Design for a Turned Wooden Box, of which the following is a specification, reference being had to the accompanying drawings, in which—

Figure 1 is an elevation; Fig. 2, a plan, and Fig. 3 a vertical section.

The general configuration of the box is round; and the leading features of my design consist in the cylindrical configuration with flat top and bottom and parallel sides and with a large raised circular bead at the top edge and a large flat rib at the bottom edge and the pairs of small raised circular beads adjacent thereto.

The design of the cover comprises the plain parallel sides $a a$, the flat top b , the large

raised circular bead c at the edge or corner, and the pair of small raised circular beads d adjacent thereto.

The design of the body comprises the plain 25 parallel sides $e e$, corresponding with the parallel sides $a a$ of the cover, the flat bottom f , the large raised flat rib g at the edge or corner, having a surface parallel with the sides $e e$, and the pair of small raised circular beads h 30 adjacent to the flat rib g and which beads h are similar to the beads d of the cover.

What I claim is—

The design for a turned wooden box, substantially as shown and described.

Signed by me this 9th day of November, 1899.

WEBSTER C. ESTES.
